UNITED STATES PATENT OFFICE.

GEORGE L. LAMB, OF NAPPANEE, INDIANA.

RUG-BEATER.

1,263,775.

Specification of Letters Patent. Patented Apr. 23, 1918.

Application filed November 26, 1917. Serial No. 203,935.

To all whom it may concern:

Be it known that I, GEORGE L. LAMB, a citizen of the United States, residing at Nappanee, in the county of Elkhart and State 5 of Indiana, have invented certain new and useful Improvements in Rug-Beaters; and I do hereby declare the following to be a full, clear, and exact description of the invention, such as will enable others skilled in the art 10 to which it appertains to make and use the same.

My invention relates to rug beaters, that is to devices for beating dust from rugs and carpets, and has particular relation to those 15 of the type in which the beater is held in position by the foot and actuated by the hand of the operator to deliver a succession of blows upon a rug or carpet, in order to drive out the dust and filth. Usually in 20 cleaning a rug or carpet, it is taken out of doors, spread upon the grass and beaten with sticks or clubs. Sometimes it is hung upon a line and beaten, sometimes it is held at the ends and shaken. In all of these the 25 fabric is apt to be injured or the work unevenly and improperly done. In using a device of the character of mine the fabric is spread upon the grass, fully supported everywhere, and is then subjected to a succession 30 of rapid smart blows just vigorous enough to drive out the dust without hurting the fabric. The device is moved over the carpet as needs be, and the dust removed without the excessive fatigue induced in the operator's 35 back by the ordinary hand-held beaters, when the carpet is flat and without the strain upon the carpet which it gets when hung over a line, though my device may, in some 40 circumstances be used to beat carpets where so hung. Devices like mine may also be used to clean carpets and rugs in their places of use, *i. e.* on the floor, though this will usually be found objectionable as is obvious.

One of the features, among others, of my 45 present invention is the construction of the beater crank-shaft and crank, integral, all of a suitable piece of bent and twisted wire, which cannot get out of order or be injured. Another feature is the provision of a structure 50 in which the actuating handle may be readily detached. My way of securing the foot piece or stirrup piece is another.

Other features of novelty will be apparent in the description.

55 Figure 1 is a perspective view of my de-

vice complete in full lines, and in dotted lines in operative position.

Fig. 2 is a bottom view showing my base member, and the groove in which the crank is hinged, and

60 Fig. 3 is a view similar to Fig. 2 showing a modification.

In the drawings, 1 represents my beater made of a piece of wire looped at 2 and crossed at 3. The right-hand leg, Fig. 1, is 65 bent at substantial right angles to form a crank shaft 4, which crank shaft meets the other leg at 5, is twisted together with it, the two being bent at 6 to form a crank and continued in the parallel arms 7 which form 70 spring supports for the pintles 8 formed by bending said arms at right angles. These engage suitable sockets 9 in the ferrule 10 of an actuating handle 11. The crank 4 is held in a groove, 12, formed in the underside or 75 bottom of base member 13, formed of hard wood or other suitable substance, by means of staples 14. Upon the two ends of the crank shaft, as close to the base piece as practicable, I pivotally mount a folding foot-holding 80 piece or stirrup 15. This stirrup so called, while preferably pivoted for folding, may be rigid with the foot piece. The upper part of the base piece is flat and the lower part or underside flat and smooth so 85 that the operator, with her foot thrust through the stirrup, may readily hold the base piece in position and move the device about as she wishes. Ready movement may be still further facilitated if desired by rollers, 16, a pair being shown in Fig. 3 mounted 90 upon the crank shaft.

It will be seen that I have produced a simple, strong and durable rug beater with durable and efficient holding and actuating 95 means. The beater proper is made of stiff wire, say No. 6 gage, and the handle and foot block or base piece of maple or other suitable wood or other material. The crank being made of the twisted wire is strong 100 and rigid just where strength and rigidity are needed, while the long flexible beater is integral therewith and receives without play or lost motion all the impulse given to the crank by the reciprocated handle and may be 105 made to whip or beat a fabric with accurately gaged force and direction. The spring arms 7 permit the ready detachment of the handle 11, the loop, 15, may be folded down and the whole device knocked down 110

and made to occupy a very small space. It will be noted that my beater 1 is mounted on the twisted wire crank-shaft oblique to the crank. This mounting insures an inclined position of the beater when the crank is horizontal and thus effects quick approach of the beater to the work. At the same time the device may be almost instantly set up ready for use, without the use of tools, all that is necessary being to spring back the arms 7 to permit the pintles 8 to snap into the sockets, and if necessary bend up the loop 15 to position. This may be rigid with the crank, if desired. The operator's foot is indicated in dotted lines at 17.

It will be noted that I have thus produced a neat, economical, and efficient device.

What I claim as new and desire to secure by Letters Patent of the United States is:—

20 1. In a rug beater, in combination, a grooved base member, a rock-shaft journaled in said groove, a beater member integral with said rock-shaft on one side of said base member, a crank also integral with said rock-shaft on the other side of said base member, said beater, rock shaft and crank being made with a single piece of wire, and a handle pivotally secured to said crank whereby the crank may be oscillated, the integral shaft turned, and the integral beater oscillated while the device is held in position by the foot of the operator.

30 2. In a rug beater, in combination, a base member, a beater member, rock-shaft and crank-member, all made of a single piece of wire twisted at one place, the crank member being formed in the twisted part, said rock shaft journaled in said base member, and a reciprocable handle to which said crank member is adapted to be attached.

40 3. In a rug beater, in combination, a base member, a wire beater member, a crank shaft made of one strand of the wire of said beater member bent therefrom at one side of said base member and pivoted on the underside of said base member, a crank formed of a continuation of said strand and another strand of said beater, brought to the other side of said base member twisted with the first-named strand and bent to form a crank, and a reciprocable handle adapted to be engaged by said crank to actuate said beater.

45 4. In a rug beater, in combination, a base

member, a wire beater member, a crank shaft made of one strand of the wire of said beater member bent therefrom at one side of said base member and pivoted on the underside of said base member, a crank formed of a continuation of said strand and another strand of said beater, brought to the other side of said base member twisted with the first-named strand and bent to form a crank, the continuation of said strands after the crank being straight parallel and bent at the ends to form spring pintles for engaging 65 sockets in a handle, and a socketed handle, with which said pintles may engage.

5. In a rug beater, in combination, a grooved base member, a beater member, a crank shaft upon which said beater member 70 is mounted to be oscillated, said shaft pivoted to the underside of said grooved base member in the groove thereof, a foot holding loop pivoted upon said shaft with the sides of said base member; a crank secured to said shaft and means adapted to be secured to the crank for oscillating the shaft and actuating the beater.

6. In a rug beater, in combination, a beater member, a base member, a shaft for actuating a beater member pivoted to the under side of said base member and a foot holding loop pivoted upon said shaft, for folding, the shaft and the beater being of one integral piece of wire.

7. In a rug beater, a beating device, a crank shaft, and a crank, all made of a single piece of wire, means to which the crank shaft is secured for holding the device, the two ends of said wire forming the crank, and means attachable to said extended ends for actuating the beater.

8. In a rug beater, a beating device, made of a wire looped and crossed, a leg of one of the crossed wires being bent over after the crossing to meet the other leg, both legs being then continued in substantially the bent direction, twisted together, and bent in the twist to form a crank, the ends of the wires after the twist being continued parallel and then bent inward toward each other to form pintles, means for supporting said device, and means whereby it may be actuated.

In testimony whereof I affix my signature.

GEORGE L. LAMB.
